DESIGN FOR A POLARIMETER OR THE LIKE

William F. Peck, Snyder, and Roger S. Estey, Buffalo, N. Y., assignors to Spencer Lens Company, Buffalo, N. Y., a corporation of New York

Application October 1, 1940, Serial No. 95,532

Term of patent 14 years

To all whom it may concern:

Be it known that we, William F. Peck and Roger S. Estey, citizens of the United States, residing at Snyder and Buffalo, respectively, in the county of Erie and State of New York, have invented a new, original, and ornamental Design for a Polarimeter or the like, of which the following is a specification, reference being made to the accompanying drawings, forming a part thereof.

Fig. 1 is a perspective view of a polarimeter or the like embodying our design;

Fig. 2 is a side elevation of the polarimeter or the like shown in Fig. 1; and

Fig. 3 is a top plan view thereof.

The characteristic features of the design are shown in full lines in the drawings.

We claim:

The ornamental design for a polarimeter or the like, substantially as shown and described.

WILLIAM F. PECK.
ROGER S. ESTEY.
